TOBACCO ASH RECEPTACLE

Marion Talbert Dick, Des Moines, Iowa, assignor
to Cadet Smokestands Company, Des Moines,
Iowa, a business trust

Application July 10, 1946, Serial No. 682,578

3 Claims. (Cl. 220—20.5)

1

The principal object of my invention is to provide a tobacco ash receptacle that has a manually operated trap door operating in conjunction with a detachable container such as a glass jar.

A further object of this invention is to provide a tobacco ash receptacle of the trap door type having a rigidly secured operating handle extending above the trap door, but without restricting or interfering in any way with the hopper top opening.

A still further object of my invention is to provide a tobacco ash receptacle of the trap door type that has an operating means directly and rigidly connected to the trap door capable of entering and passing below the top plane of the hopper top when the trap door is in an extreme open position.

A still further object of this invention is to provide a tobacco ash receptacle having a hopper top with a relatively large opening communicating directly with a detachable container.

A still further object of this invention is to provide a tobacco ash receptacle of the trap door type that has an operating handle means directly connected to the trap door and so positioned as to be easily manually operated while at the same time protected against accidental damage.

A still further object of this invention is to provide a tobacco ash receptacle that lends itself to packing and shipping.

A still further object of my invention is to provide a tobacco ash receptacle that is refined in appearance, economical in manufacture, and durable in use.

These and other objects will be apparent to those skilled in the art.

My invention consists in the construction, arrangement and combination of the various parts of the device, whereby the objects contemplated are attained as hereinafter more fully set forth, pointed out in my claims and illustrated in the accompanying drawings, in which:

Fig. 1 is a side-sectional view of the upper portion of a smokestand showing my invention.

Fig. 2 is a top plan view of my tobacco ash receptacle.

Fig. 3 is a bottom view of my invention taken on line 3—3 of Fig. 1, and more fully illustrates its construction.

The objection to most smokestands on the market is that they do not have trap doors with the operating means connected directly and rigidly to the same to permit easy and continued operation and to facilitate cleaning. Another objection is that substantially all smokestands are difficult to empty and clean the receptacle portion 55

2

of tobacco oils, stains, and odors. This is particularly true of all smokestands having metal containers. I have overcome such objections by providing a direct drive trap door opening into a detachable, cleanable glass or like jar, and which I will now describe in detail.

The numeral 10 designates a smokestand standard of any suitable design provided it has a well 11 to receive my hopper top, trap door, and container. In the drawing, this member is of tubular form at least at its upper end portion. Such a standard may be provided with side handles 12 for lifting purposes and if desired, a tray or table top 13. This tray 13 may be detachable or secured such as I have shown in the drawings, wherein the same has a collar 14 embracing the member 10 and riveted or spot welded thereto. This tray may rest on the top of the handles 12 for greater structural strength. It is to such or similar smokestand that I install my invention. The numeral 15 designates the hopper top having a downwardly extending outer marginal rim designed to embrace the upper end of the smokestand and a downwardly and inwardly sloping hopper 16 in its top center and which terminates in an opening 17. This downwardly and inwardly sloping portion 16 may be of any design, but the most successful is of the oblong type, as shown in Fig. 2. Such a slope opening not only guides the ashes and like material into the device, but with the trap door, acts as an efficient cigar or cigarette rest and is far superior to the usual cigarette and cigar rests which become soiled and are not easily cleaned. The numeral 18 designates a base plate having an opening surrounding the under side of the portion 16, as shown in Fig. 1. This horizontal plate may be secured to the hopper top by any suitable means such as spot welding, soldering, rivets, bolts, or the like and has its bottom in a plane slightly above the opening 17. In the drawings, I show this plate secured to the hopper top by bolts 19 and if desired, two of these bolts may be in the form of a U-handle bail 20. Such a handle bail 20, if used, may be employed for lifting the entire unit from the smokestand. As this bail extends above the hopper top it may be desirable to detach the same for shipping purposes and if desired it may be dispensed with entirely by using the trap door operating handle for lifting the unit. When the tray 13 is not used, the bail 20 is definitely not necessary, as one may easily remove my unit from the smokestand by grasping the under side of the outer marginal flange of the hopper top. The numeral 21 designates a

threaded jar rim top secured by any suitable means such as spot welding, soldering, or like, on the under side of the plate 18 and capable of receiving and holding a jar 22. This threaded rim 21 and jar 22 are preferably of standard design such as an ordinary Kerr-Mason glass jar and its rim top. Such glass jars and top rims are common in most all homes and stores and are used for canning. Obviously, if by accident, a jar 22 is broken, another one may be easily and quickly obtained for replacement purposes. When purchasing such standard jars a closing plate is present between the rim and jar, but in my use, this member is eliminated as it is desirable that the rim 21 embrace the opening 17 and that the opening 17 communicate directly with the inside of the detachable jar 22. Any size length of glass jar may be used and in the drawings, I show a relatively short jar for conserving drawing space. I have found that tobacco stains, odors, and gums may be easily and quickly washed from a glass container, which is not possible with a metal container. For this reason, I highly recommend the use of a glass jar and one with a wide mouth opening to facilitate washing and cleaning. However, I do not wish to confine myself entirely to a glass jar and it is obvious that containers of other materials such as metal, plastic, and clay may be used. One advantage of a glass jar, however, is that it is transparent and it is a simple matter to observe whether or not the glass jar is in need of emptying.

To remove the jar 22 for emptying or cleaning, it is merely necessary to lift the unit upwardly from the smokestand and detach the glass jar by unscrewing it from the rim 21. After emptying and cleaning, the jar may be as easily replaced. It will be noted that while the outer marginal rim of the hopper top embraces the upper end of the smokestand the plate 18 rests inside the opening 11 with the jar 22. By this construction, the plate 18 centers the unit on the smokestand and prevents undesirable lateral movement. The unit is supported by its outer marginal edge resting on the top of the tray 13, as shown in Fig. 1, or if desired, the under side of the hopper top may rest directly on the upper marginal edge of the smokestand 10. This latter method will always be used when a tray 13 is not present. Such an all around circular support rigidly maintains the device and no rocking of the jar inside the smokestand is possible. Furthermore, the hopper top construction spaces the jar 22 inside the smokestand, without engaging its inner side wall.

I will now describe my direct drive trap door. The numeral 23 designates a downwardly extending U-shaped bearing member on the under side of the plate 18, inside the threaded rim 21, and at one side of the opening 17. The numeral 24 designates a small shaft extending through the bearing member. However, in case my trap door is used independently of the plate 18 and in conjunction with or without the jar container 22, it is understood that the trap door shaft 24 may be operatively secured to the hopper top in any suitable manner. The numeral 25 designates a trap door secured by any suitable means to the shaft 24 such as bearing ears 26 embracing the shaft 24. The numeral 27 designates a coil spring embracing the shaft 24, having one end engaging the under side of the trap door 25, and its other end operatively engaging the plate 18. By this construction, the coil spring 27 will yieldingly hold the trap door upwardly for closing the

hopper top opening 17. The numeral 28 designates an operating rod of flat or round construction in cross-section having its lower end rigidly secured to the trap door 25 at a point outside the general outline of the opening 17. This feature is highly important and is accomplished by forming a walled recess opening 29 in the portion 16 of the hopper top adjacent to the opening 17, as shown in all of the figures. This walled recess has its open bottom in the same plane as the opening 17 and is therefore closed by the trap door when the trap door is in a closed position, as shown in Fig. 1. By this arrangement, the operating handle 28 may extend directly upwardly from the trap door, be rigidly secured thereto, and yet be outside the general outline of the opening 17. The operating handle therefore will neither restrict nor interfere in any way with the trap door opening 17 and the entire hopper top may be easily kept clean. The recess 29 is centrally located, as shown in Fig. 2, and extends at each side and to the back of the directly connected operating handle rod, thereby substantially supporting the rod and trap door and maintaining the same in true alignment throughout the useful life of the device. In order that the operating handle will be substantially clear of the entire downwardly and inwardly sloping hopper 16 the same extends upwardly only a short distance and then is bent outwardly and upwardly parallel with the sloped opening and then upwardly, as shown in Fig. 1. The numeral 30 designates a ball or like handle on the upper free end of the member 28. To open the trap door it is merely necessary to grasp the ball and move it toward the opening 17 and against the action of the spring 27. The trap door will open inside the container, as shown by dotted lines in Fig. 1, and the handle ball will be at least below the upper surface of the hopper top. This is highly important for shipping purposes as when the ball and lever are in such lowered position they are protected and free from possible damage in transit. The trap door may be held in such open position by a piece of paper or like placed inside the jar. This feature is highly necessary when the device is made without a bail 20 or when the bail is detached. With the operating handle and ball below the top surface of the hopper top the carton holding the smokestand will lay directly on and above the hopper top. Obviously, if the operating handle were not capable of passing below the surface of the hopper top it would be necessary in shipping to remove the hopper top to prevent damage of the trap door and in many types of smokestands this is absolutely necessary but highly objectionable inasmuch as more carton space is necessary and the smokestand reaches its destination not assembled. By placing the direct drive operating handle on top of the hopper top, the operating mechanism is prevented from serious damage in use when the smokestand is accidentally tipped over. Obviously, in my construction, when a smokestand is tipped over the operating handle will not be struck or damaged. Furthermore, it is properly positioned at the top of the hopper top for easy reach and use. By being directly connected to the trap door no complicated mechanism is present and by grasping the handle the trap door may be rigidly held in a closed position for wiping dirt from the entire top of the hopper top.

Some changes may be made in the construction and arrangement of my improved tobacco

ash receptacle without departing from the real spirit and purpose of my invention, and it is my intention to cover by my claims any modified forms of structure or use of mechanical equivalents which may be reasonably included within their scope.

I claim:

1. In a device of the class described, a hopper top having downwardly and inwardly extending walls which terminate in an opening, a plate member secured to the under side of said hopper top, a threaded member secured on the under side of said plate member embracing the opening in said hopper top and designed to engage a container, a trap door hingedly secured to said plate member and capable of closing the opening in said hopper top when in a closed position, a means for yieldingly holding said trap door in a closed position, a recess formed in the downwardly and inwardly extending portion of said hopper top, and an operating handle directly secured to said trap door and extending through said recess when said trap door is in a closed position.

2. In a device of the class described, a hopper top having downwardly and inwardly extending walls which terminate in an opening, a recess formed in the lower edge portion of said downwardly and inwardly extending walls of said hopper top, a trap door capable of closing the opening in said hopper top when in a closed position, a means for yieldingly holding said trap door in a closed position, and an operating handle secured to said trap door and extending through

said recess when said trap door is in a closed position.

3. In a device of the class described, a hopper top having downwardly and inwardly extending walls which terminate in an opening, a recess formed in the lower edge portion of said downwardly and inwardly extending walls of said hopper top having its two sides and back closed, a trap door capable of closing the opening in said hopper top when in a closed position, a means for yieldingly holding said trap door in a closed position, and an operating handle secured to said trap door and extending through said recess when said trap door is in a closed position.
